UNITED STATES PATENT OFFICE.

PAUL PARCELLS, OF CHICAGO, ILLINOIS, ASSIGNOR TO GEO. WHITING COMPANY, OF CHICAGO, ILLINOIS, A CORPORATION OF ILLINOIS.

BENDING-ROLLS.

1,349,690.

Specification of Letters Patent. Patented Aug. 17, 1920.

Application filed August 30, 1915. Serial No. 48,108.

To all whom it may concern:

Be it known that I, PAUL PARCELLS, a citizen of the United States, residing at Chicago, in the county of Cook and State of Illinois, have invented certain new and useful Improvements in Bending-Rolls, of which the following is a specification.

My invention relates to that class of machines known as bending rolls used for the purpose of bending or of bending and corrugating metal sheets and the object thereof is to provide a comparatively simple, efficient and reliable machine of this character possessing advantages both in construction and mode of operation. My machine is particularly characterized by the employment of an end bearing for the top roll which bearing swings in a plane at right angles to the axis of such roll and whose swinging movement, moreover, causes, through intermediate operating connections, a movement bodily of such top roll away from the bottom roll so as to permit the work to be readily removed from between the rolls.

My machine is further characterized by the movement of the bottom roll in such manner that it may yield and also by the provision of means for relieving the yielding pressure which holds such roll in its working position.

My machine is still further characterized by efficient and reliable mechanism for moving or adjusting the back roll by power toward and away from the top roll.

My invention embodies other advantages and novel features of construction and mode of operation which will be apparent from the description hereinafter given.

While I have herein shown and will hereinafter describe my machine as constructed for the manufacture of corrugated pipe, yet it will be understood that my invention is not limited to that particular use, although such use accentuates the value of the invention.

In the drawings, Figure 1 is a top plan view of my machine; Fig. 2 a front end elevation thereof; Fig. 3 a cross-section on line 3—3 of Fig. 1; Fig. 4 a cross section on the line 4—4 of Fig. 1; Fig. 5 a horizontal section on the line 5—5 of Fig. 3; Fig. 6 a vertical section on the line 6—6 of Fig. 3; Fig. 7 a detail horizontal section on the line 7—7 of Fig. 6; Fig. 8 a perspective 55 of the spring rod shown in Fig. 6; and Fig.

9 a detailed sectional view taken on the line 9—9 Fig. 1; and Fig. 10 a detail of the removable bearing for the outer end of the top roll.

Referring to the particular embodiment of my invention as herein shown without limiting myself specifically thereto, the machine is provided with any suitable character and size of main frame which is here shown as comprising two parallel I-beams 1 adapted to rest on the floor or other support and adapted to support three vertical frames in which the moving parts have their bearings. These frames comprise a front end frame 2, a back end frame 3 and an intermediate or middle frame 4. There are three rolls, to wit, the top roll 5, bottom roll 6 and back roll 7 whose relative arrangement is best shown in Fig. 3. The top roll has its main bearing at its intermediate portion in an eccentric trunnion 8 forming a part of a yoke 9 having another trunnion 10 bearing against the end frame 3. The top roll has an extended shaft 5^a passing through the two trunnions 8 and 10 of the yoke and having its end journaled in the end frame 3, Fig. 1. In so far as this particular construction is concerned, it is substantially the same as shown in Patent Number 1,195,714, granted August 22, 1916, upon my prior application to my assignee, George Whiting Company. The purpose of this mounting of the shaft of the top roll in an eccentric bearing or trunnion is to cause such roll to be swung away from the bottom roll whenever the yoke is oscillated in a manner hereinafter explained.

The bearing at what may be termed the outer end of the top roll is of novel construction and operation inasmuch as it is adapted to swing in a plane at right angles to the axis of rotation of its roll. As shown more particularly in Figs. 1, 2, 6 and 10, this outer bearing comprises an arm 11 which is hook-shaped at its upper end by reason of the provision of a bearing 11^a having a lateral opening for the purpose of receiving and holding in working position the outer end of the top roll. This swinging arm is provided at its upper end with an operating handle 11^b, and is pivoted at its lower end and secured to a rock shaft 12 suitably journaled in the frames, 2, 3 and 4. This shaft is operatively connected with the yoke 9 with suitable connections with the result that when the swing-

ing arm is rocked or swung to the right in Fig. 2 so as to remove the outer bearing of the top roll the yoke and consequently the top roll are automatically swung as an incident to such swinging movement of the arm 11. These operating connections, as shown in Figs. 1 and 4, comprise a crank arm 13 and a connecting rod 14 pivotally connected at its lower end to the upper end of the crank 10 arm and at its upper end to an extended arm 10^a adjacent the outer trunnion of the yoke. It is evident that when the arm 11 is swung to the right, Fig. 2, the yoke will be swung in an opposite direction, that is, in an anti-clockwise direction as viewed in Fig. 4, with the result that the top roll will be swung upwardly and away from the bottom roll.

By preference the arm 11 is locked in working position in suitable manner as by 20 means of the pivoted latch 15 having a hook portion adapted to be engaged over a pin or projection 16 on one side of such arm, as clearly shown in Fig. 2, where the latch is illustrated in locked position.

25 Referring to the preferably detailed construction of the outer bearing of the top roll, as shown in Fig. 6, the same is provided with a bearing bushing 17 held in place on the end extension of the top roll by means of an end 30 plate or disk 18 which is itself secured to the roll by means of the central screw 19. The bushing 17 is made with an angular outer surface being hexagonal in the present instance as seen in Figs. 2, 6 and 10, and the 35 construction and arrangement of the parts are such that when the arm 11 is swung to working position the bearing 11^a will engage the bushing which will partially turn or center itself with respect to such bearing if it is 40 not already in such position when the bearing engages the same, see particularly Fig. 10 in which the movements of the parts are indicated by arrows. It will be observed that by reason of the polygonal formation 45 of the bushing 17 and the corresponding shape of the bearing 11^a, the bushing is prevented from turning, and the contacting upper and lower plane surfaces of the bushing and bearing extend considerably beyond the diametrical center of the bearing 50 toward the edge of the opening. A secure and substantial support to the outer end of the top roll is therefore attained by this construction.

55 Referring next to the bottom roll 6 the same is mounted in bearing boxes or journals 20, which are movable vertically in the vertical guides 21 provided in the end frames 2 and 4. These journals are mounted on the 60 vertical rods 22 having their bearings in said frames 2 and 4 and supported at their lower ends by a pivotal connection with two similar substantially horizontal levers 23. These levers are pivoted at their outer ends 65 at 24 in brackets 25 secured to the sides of

the end frames 2 and 4 preferably in an adjustable manner. By preference the lower ends of the rods 22 are provided with sockets which receive the rounded bearing projections 26 and thereby form a ball and socket 70 joint or pivotal connection. The inner adjacent ends of the two levers 23 are pivotally connected by means of two parallel links 27 between which links and between the ends of the levers 23 is arranged a semi-circular 75 block 28 having rounded top edges and having also a rectangular block portion 28^a fitting crosswise and above the top edges of the two links 27. The block 28 is secured to these links by means of the cross pin 29. 80 The blocks 28 and 28^a are provided with a vertical rod 30 which is held upwardly with a yielding pressure by means of the coiled spring 31. This spring bears at its upper end against a plate 32 which is held in place 85 on the rod by means of the nut 33 screwing on the upper end thereof and such spring bears at its lower end against the plate 34 contained within a short spring barrel or cylinder 35 which is secured to and supported by the cross member 36 of the main frame.

90 The spring 31 and the connections between it and the journal boxes 20 constitute means for yieldingly holding the bottom roll in working position so that this roll may yield for different thicknesses of metal plate and more particularly for the joint or lap such as occurs in corrugated or culvert pipe. Moreover the construction and arrangement 100 is such that the effect of the yielding mechanism may be relieved at the will of the operator, thereby dropping the bottom roll or at least removing the pressure thereof against the top roll with the result that the swinging arm 11 can be more readily operated, that is with less exertion. The means for relieving this pressure at the will of the operator consists of a lever or treadle 37 arranged at the front end of the machine in 110 position to be operated by the foot of the operator and just at or prior to the time he grasps the handle 11^b of the arm 11 for the purpose of swinging the same. This treadle is secured at one end to a rock shaft 38 115 which has its bearings in one of the I-beams 1. This shaft is provided at its inner end with a crank arm 39 to which is pivotally connected a link 40 whose upper end is itself pivotally connected to one end of a horizontal link 41, the other end of such latter link being pivotally supported or fulcrumed at 42 on the lower side of the cross member 36. This link 41 is enlarged at its intermediate portion and provided with a slot 41^a to accommodate the block 28^a. This link therefore is adapted to bear against the transversely rounded top surfaces at the ends of the semicircular portion of the block 28, on 120 opposite sides of the block 28^a, but is held to 125

130

normal horizontal position as shown in Fig. 3 by means of a vertical rod 43 secured to one end of the link and spring-pressed upwardly by means of a spring 44. When the treadle is depressed the yielding supporting means for the journal bearings will be disabled inasmuch as the outer end of the link 41 is thereby moved downwardly through the operating connections and consequently the links 27 and the levers 28 are likewise depressed with the result that the upward tension of the vertical rods 22 will be overcome, and the upward pressure on the journal boxes will consequently be relieved.

Referring next to the back roll 7 the same is mounted in bearing boxes or journals 45 movable longitudinally of bearing guides 46 formed in the vertical frames 2 and 4 whereby the boxes may be moved or adjusted toward and away from the top roll 5. These boxes are adapted to be moved by hand by operating the power mechanism. As herein shown the boxes are secured at the upper ends of screw shafts 47 having suitable bearings in said frames 2 and 4 and each being provided with a beveled gear 48 threaded on its screw shaft. For the purpose of operating these beveled gears in unison a common horizontal shaft 49 is employed at the ends of which similar beveled pinions 50 are secured adapted to mesh with the beveled gears 48. The shaft 49 is provided with two similar spur gears 51 and 51^a one of which meshes with the spur gear 52 and the other with an idler or reverse gear 52^a which in turn meshes with a spur gear 52^b. (Fig. 9). The drive shaft 53 is provided with friction clutches 54 and 54^a which being of conventional construction need not be described in detail except to say that the gears 52^b are secured to those members of the clutches which are mounted freely upon the shaft 53. These clutches are employed so as to provide a yielding drive for moving the journal boxes in opposite directions and yielding particularly when the back roll is forced against the top roll with a predetermined pressure, the clutches will yield or slip. These clutches are controlled in a suitable manner as by means of the lever 55 arranged at the operator's side of the machine and having operating connections which here consist of a horizontal rod 56 extending across the machine and pivotally connected to a bell crank 57 which in turn is pivotally connected to the operating rod 58 and yoke 58^a which operates the clutches. In the position shown in Fig. 1, the sleeve 54^b which is shifted by the yoke against the pivoted arms 54^c of one or the other clutch to render it operative is in neutral position. When shifted to the left the clutch 54 is operated and the gears 51 and 52 are driven to move the back roll toward the top roll. When the sleeve is shifted to the right, the clutch

54^a is operated and the gears 51^a, 52^a and 52^b are driven to move the back roll away from the top roll. By preference the shaft 53 is extended beyond the end of the end frame 2 so that it may be operated by hand. (Fig. 1.)

The driving connections for the rolls and the drive shaft 53 comprise in the first instance a pulley 59 having a main drive shaft 60 journaled in the frames 3 and 4 and having at its outer end a pinion 61 which meshes with the large gear 62 secured to the countershaft 63, having its bearings in the frames 3 and 4. The shaft 63 carries a pinion 64 which meshes with the pinion 65 secured to the extended end of the bottom roll for the purpose of driving the latter. The pinion 65 meshes with another pinion 66 which is secured to the extended end of the top roll. In addition the pinion 65 meshes with a pinion 67 which in turn meshes with a pinion 68 secured to the extended end of the back roll for the purpose of rotating the latter. Referring to the connections between the main drive shaft 60 and the drive shaft 53 the same comprise the gear 69 secured to the shaft 60 and the intermeshing gear 70 secured to the shaft 53.

It will be understood that the construction and arrangement of the yielding supporting means for the journal bearing are such that one of the bearings may be permitted to yield more than the other which is desirable in certain classes of work inasmuch as the product going through the machine may be thicker at the end.

I claim:

1. In a machine of the class described, the combination of bending rolls, and a removable bearing for one end of one of said rolls and arranged to swing in a plane at right angles to the axis of rotation of said roll, said latter roll having a free polygonal bearing bushing and said removable bearing having a corresponding polygonal seat adapted to engage said bushing adapted to be engaged by said removable bearing.

2. In a machine of the class described, the combination of bending rolls, and an arm located adjacent one end of one of said rolls and arranged to swing in a plane at right angles to the axis of rotation of said roll, said end of the roll having a free polygonal bearing bushing and said arm having a corresponding polygonal bearing portion adapted to engage said bushing.

3. In a machine of the class described, the combination of bending rolls, and an arm located adjacent one end of one of said rolls and arranged to swing in a plane at right angles to the axis of rotation of said roll, said end of the roll having a freely rotatable bearing bushing externally angular, and said arm having a bearing portion adapted to engage said angular portion of the bushing.

4. In a machine of the class described, the combination of bending rolls, and an arm located adjacent one end of one of said rolls and arranged to swing in a plane at right angles to the axis of rotation of said roll, said arm having a side opening forming a bearing and said end of the roll having a freely rotatable bearing bushing externally angular which is adapted to be received and held by said opening.
5. In a machine of the class described, the combination of bending rolls, means for shifting one of them bodily toward and away from its adjacent roll in parallel relation thereto, a removable bearing for one end of said roll arranged to be shifted into and out of bearing, and operating connections between said removable bearing and said means.
6. In a machine of the class described, the combination of bending rolls, means for swinging one of them bodily toward and away from its adjacent roll in a curved path and in parallel relation to said adjacent roll, an arm located adjacent one end of said swinging roll and pivoted to swing, said arm having a bearing to engage said end of the roll, and operating connections between said arm and said means.
7. In a machine of the class described, the combination of top, bottom and back rolls, a bearing for the top roll adapted to rock in a plane at right angles to the axis of rotation of each roll, means for swinging the roll away from the other rolls in a curved path and in parallel relation to such other rolls, and means for substantially simultaneously operating said bearing and said means.
8. In a machine of the class described, the combination of top, bottom and back rolls, a bearing for the top roll adapted to rock in a plane at right angles to the axis of rotation of each roll, said bearing comprising a rock arm having a side opening forming a bearing proper, means for swinging the roll away from the other rolls in a curved path and in parallel relation to such other rolls, and means for substantially simultaneously rocking said arm and operating said means.
9. In a machine of the class described, the combination of bending rolls, movable journal bearings for the bottom roll, and yielding supporting means for said bearings comprising a pair of levers operatively connected therewith and a spring coöperating with both of the levers to hold the bearings in working position with a yielding pressure.
10. In a machine of the class described, the combination of bending rolls, movable journal bearings for the bottom roll, and yielding supporting means for said bearings comprising a pair of levers operatively connected therewith, a link connecting the inner adjacent ends of the levers, and a spring operatively connected with the link.
11. In a machine of the class described, the combination of bending rolls, movable journal bearings for the bottom roll, and yielding supporting means for said bearings comprising a pair of levers operatively connected therewith, a link connecting the inner adjacent ends of the levers, a rod bearing against the link, and a spring connected with the rod.
12. In a machine of the class described, the combination of bending rolls, movable journal bearings for the bottom roll, a spring bearing against a fixed abutment and arranged to yieldingly support said bearings, and independent mechanism for further compressing said spring against said abutment and thereby relieving the bearings of the effect thereof.
13. In a machine of the class described, the combination of bending rolls, movable journal bearings for the bottom roll, and yielding supporting means for said bearings comprising a pair of levers operatively connected therewith, a spring coöperating with both of the levers to hold the bearings in working position with a yielding pressure, and mechanism coöperating with the levers for disabling the spring with respect to its effect upon the levers.
14. In a machine of the class described, the combination of bending rolls, movable journal bearings for the bottom roll, and yielding supporting means for said bearings comprising a pair of levers operatively connected therewith, a spring coöperating with both of the levers to hold the bearings in working position with a yielding pressure and tending to move them in one direction, a link connecting the adjacent ends of the levers, and manually operative mechanism for moving such levers in the opposite direction to relieve the bearings of the spring pressure.
15. In a machine of the class described, the combination of bending rolls, movable journal bearings for the bottom roll, and yielding supporting means for said bearings comprising a pair of levers operatively connected therewith, a spring coöperating with both of the levers to hold the bearings in working position with a yielding pressure and tending to move them in one direction, a link connecting the adjacent ends of the levers, a member adapted to bear against the link to move the levers in the opposite direction, and manually operative means for actuating said member.
16. In a machine of the class described, the combination of bending rolls, movable journal bearings for the bottom roll, and yielding supporting means for said bearings comprising a pair of levers operatively connected therewith, a spring coöperating with both of the levers to hold the bearings in working position with a yielding pressure

and tending to move them in one direction, a link connecting the adjacent ends of the levers, a pivoted link bearing downwardly upon the link to move the levers in the opposite directions, a treadle and operating connections between it and the link.

17. In a machine of the class described, the combination of bending rolls, movable journal bearings for the bottom roll, yielding supporting means for said bearings, including a pair of levers, rods between the levers and bearings, and a spring coöperating with the levers to hold the bearings in working position with a yielding pressure.

18. In a machine of the class described, 15 the combination of bending rolls, movable journal bearings for the bottom roll, yielding supporting means for said bearings, including a pair of levers having an adjustable fulcrum and operatively connected with 20 the bearings, and a spring coöperating with the levers to hold the bearings in working position with a yielding pressure.

PAUL PARCELLS.
